UNITED STATES PATENT OFFICE

2,558,824

DOOR FASTENER

George E. Dath, Mokena, Ill., assignor to W. H. Miner, Inc., Chicago, Ill., a corporation of Delaware

Application January 13, 1947, Serial No. 721,707

2 Claims. (Cl. 20—21)

1

This invention relates to improvements in door fasteners for hinged doors and more particularly for hinged doors of automobile trucks.

One object of the invention is to provide a door fastener for automobile trucks comprising a rotary operating bar carried by the truck door having keeper engaging crank members adapted to cooperate with keeper means mounted on the truck above and below the door, wherein the rotary operating bar is concealed within the door structure.

A further object of the invention is to provide a door fastener as set forth in the preceding paragraph, wherein the assembled rotary operating bar and keeper engaging members are arranged to be applied to the door as a unit which is entered through an opening at the top of the door and is maintained in its assembled operative condition with respect to the door by shouldered engagement with a bearing seat provided at the lower portion of the door.

Other objects of the invention will more clearly appear from the description and claims herein-after following.

In the accompanying drawings forming a part of this specification, Figure 1 is a rear elevational view of a portion of the body of an automobile truck provided with a pair of hinged doors, illustrating my improvements in connection therewith. Figure 2 is a transverse, vertical sectional view, on an enlarged scale, corresponding substantially to the line 2—2 of Figure 1. Figure 3 is a broken top plan view of the right hand door shown in Figure 1, the view being taken at the inner edge of the door. Figure 4 is a broken horizontal sectional view, corresponding substantially to the line 4—4 of Figure 2. Figure 5 is a horizontal sectional view, corresponding substantially to the line 5—5 of Figure 2, showing the cooperating keeper member, the door being omitted in this view. Figure 6 is a front elevational view of the keeper member shown in Figure 5.

In said drawings, 10 indicates the rear wall of an automobile truck having a door opening 11 therein, closed by a pair of hinged doors 12 and 13. Each door is provided with the usual hinges 14—14 along the vertical outer edges thereof, by which the door is swingingly supported. The doors 12 and 13 are of well-known design, the door 12, as shown in Figures 2, 3, and 4, comprising top and bottom Z-bars 15—15, front and rear walls 16 and 17 in the form of sheet metal plates secured to the vertical flanges of the Z-bars 15—15, and the usual vertical end walls connect-

2

ed by front and rear walls, the inner end wall only being shown, said end wall being indicated by 18. The door 13, the details of which are not shown, is of a construction similar to the door 12, and the doors 12 and 13 have their meeting edges beveled so that the door 12 overlaps the door 13 when the same are closed. The door 12 has a portion of the front wall inwardly offset, as indicated at 19, to provide a laterally elongated pocket 20, adapted to accommodate the operating handle lever of the door fastener, as hereinafter described.

My improved door fastener, as shown in the drawings, comprises broadly an operating bar 15 A, keeper engaging end members B—B, keepers C—C, and an operating handle lever D.

The bar A is in the form of a hollow cylindrical tube, vertically disposed between the front and rear walls 16 and 17 of the door 12 and extending through aligned openings 21—21 in the top and bottom walls of the pocket 20.

The end members B—B are of similar design, except as hereinafter pointed out, each end member being in the form of a thimble telescoped over the corresponding end of the cylindrical bar A and welded thereto. Each end member comprises a cylindrical sleeve-like portion 22, closed at one end, the sleeve 22 of the lower end member B being closed at its lower end and the sleeve 22 of the upper end member B being closed at its upper end. Each end member has an eccentric keeper engaging crank pin 23 extending from the closed end of the sleeve portion 22 thereof, the crank pin of the lower end member depending and that of the upper end member upstanding therefrom. The sleeve portion of the upper end member B is enlarged at its upper end to provide a cylindrical bearing portion 24 which is journaled in a circular bearing opening 25 provided in the horizontal web of the upper Z-bar 15 of the door 12. The sleeve 22 of the lower end member B is provided with an exterior annular flange 26 adjacent its lower end adapted to bear on the horizontal web of the lower Z-bar 15 of the door 12. The flange 26 is spaced inwardly from the lower end of the sleeve 22 and the sleeve thus presents a projecting cylindrical bearing portion 27 at its lower end, which is journaled in a circular bearing opening 28 provided in the horizontal web of the bottom Z-bar 15. The opening 28 of the bottom Z-bar is in vertical alignment with the opening 25 of the top Z-bar but is of smaller diameter than the opening 25, the latter being of slightly greater diameter than the flange 26 of the lower end

member to permit said flange to pass freely therethrough to allow application of the fastener to the door, as hereinafter described.

The crank pins 23-23 of the end members B-B cooperate with the keepers C-C, which are located, respectively, above and below the door 12. The keepers C-C are in the form of blocks set into the top and bottom walls of the door opening 11, as clearly shown in Figure 2. Each keeper C is provided with a diagonal cam slot 29 within which the crank pin 23 of the corresponding end member is engageable to cam the door 12 open or closed in a well-known manner as the bar A is rotated.

The operating lever D is carried by the bar A between the ends thereof, being rigidly secured to that portion of the bar which extends through the pocket 20 of the door 12. The main body portion of the lever D is in the form of an elongated arm of channel-shaped cross section, comprising a central web 30, formed with top and bottom, forwardly extending flanges 31-31. At the outer end portion, the lever D terminates in a hand grip 32, which is continuous with the web 30. At the inner end, the arm portion of the lever D is formed with a semi-cylindrical flange 33 which partly surrounds the tubular bar A in embracing relation thereto and is welded to the latter, as indicated at 34 and 35. To maintain the lever D in fixed position and prevent rotation of the bar A when the door is closed, a latch member 36 is preferably provided. This latch member may be of any suitable form, and, as shown, comprises a spring actuated pivoted latch finger 37 engaged through a suitable opening 38 provided in the vertical web 30 of the arm of the operating lever D.

In applying my improved door fastener to the door 12, the end members B-B are first assembled with the bar A by telescoping the sleeve-like portions 22-22 of the end members over the corresponding ends of the bar and welding the same thereto, as shown, the sleeves 22-22 having suitable perforations or openings 39-39 therethrough to accommodate the welding metal. The bar A with the assembled end members B-B thereon, is then applied to the door 12 by inserting the assembled unit in endwise direction from above the door, through the opening 25 at the upper end of the same. In the assembling operation, the unit is dropped downwardly until the bearing portion 27 of the lower end member B is engaged in the bearing opening of the bottom Z-bar 15 of the door with the annular flange 26 of said end member seated on the horizontal web of said Z-bar. The handle lever D is then welded to the bar A.

As is well understood by those skilled in this art, forcibly opening and closing of the door 12 is effected by camming engagement of the eccentric crank pins 23-23 with the keepers

C-C by rotation of the bar in reverse directions through swinging movement of the operating handle lever D. In forcing the door 12 closed, the operating handle lever D swings into the pocket 20 of said door, as clearly shown in Figure 4, and is automatically latched in position by the spring actuated latch finger 37 when the door has been forced home.

I claim:

1. In a hinged door construction, the combination with a door member having spaced front and rear walls and top and bottom horizontal walls connecting said spaced walls; of a rotatable operating bar having keeper engaging end members fixed to opposite ends thereof adapted to cooperate with fixed keepers, said bar being arranged vertically in the space between said front and rear walls of the door and having the end members thereof extending through and journaled in bearing openings provided in said top and bottom walls of the door; and an annular supporting flange on said lower end member having shouldered engagement with said bottom wall of the door to support said end member and bar against downward displacement, said bearing opening in said top wall of the door being of a greater diameter than the diameter of said annular flange of said lower end member to permit endwise insertion of said bar and attached end members through said opening into the space between the front and rear walls of the door.

2. In a hinged door construction, the combination with a door having spaced front and rear walls and top and bottom walls connecting said spaced walls; of a tubular operating bar rotatably mounted on said door; a lower keeper engaging end member on the lower end of said bar, said end member extending through a bearing opening in the bottom wall of said door and having an exterior annular flange supported on said bottom wall, said end member having a sleeve-like socket portion within which the lower end of the bar has a telescopic fit; an upper keeper engaging member on the upper end of said bar, said upper keeper engaging member extending through and being journaled in an opening in the top wall of said door; and a lever fixed to said bar for rotating the same.

GEORGE E. DATH.
